DESIGN FOR A STOVE.

Design No. 12,606, dated December 20, 1881.

Cut 277.

UNITED STATES PATENT OFFICE.

H. CLAY BASCOM AND CYRUS A. HODGES, OF TROY, N. Y., ASSIGNEES TO N. S. VEDDER PATTERN WORKS, BASCOM, GALBRAITH & CO., OF SAME PLACE.

DESIGN FOR A STOVE.

SPECIFICATION forming part of Design No. 12,606, dated December 20, 1881.

Application filed November 17, 1881. Term of patent 7 years.

To all whom it may concern:

Be it known that we, H. CLAY BASCOM and CYRUS A. HODGES, each a citizen of the United States, residing in the city of Troy, in the county of Rensselaer and State of New York, have jointly invented and produced a new and original Design for a Stove, of which the following is a specification, reference being had to the accompanying print, cut, or engraving of a stove 10 having said new design.

The design for the hooded urn A is composed of the lower stem-supported bowl-shaped part, b, hood c, of long concavely-conical form, and having a serrate lower rim, e', pending 15 over and distinct from the rim of the bowl b, and the lateral ornamental standards d, having the top pointed parts, d', bottom scroll-leaves, d², and intermediate parts, d³, conformed to opposite sides of the bowl and hood, 20 and supporting the latter over the former, and all shaped and arranged together so as to appear substantially as represented in the accompanying cut.

The design for the end cap-plates, B, consists of the bottom arched fillet, e, bordered above by the series of circle ornaments f, the middle upwardly-pointing curved top fillets, g, bordered below by the rectangular ornamentations h, and terminating laterally in the curved 30 and straight inclined fillets g', and the intermediate middle ornamentations, i, all shaped and arranged together substantially as shown in the aforesaid print.

The design for the balustrade C consists of 35 the central skeleton-wheel-form ornament, j, and the lateral open-work scroll-vines k k on the base-bar l, and covered by the inclined and ornamented top rail, l', all shaped and arranged together as represented in the accompanying engraving.

The side plate, D, and end door, E, are of the same general shapes as those shown in United States Design Patent No. 11,882, of July 20, 1880, but are differently ornamented.

40 The present design for the side plate, D, consists of the two compound standard-like ornaments m m, extending from the bottom to near the top of the end portions of the plate, and the compound bar ornaments n n, extending 45 along the middle parts of the top and bottom portions of the plate, all of said ornaments being composed and shaped in their several parts and arranged together substantially as shown in the aforesaid cut.

Our present design for the end door, E, consists of the middle quadrilateral raised panel, o, having the incut compound central ornament, o', the lateral compound ornaments p, the ornamental upwardly-pointed name-plate q under the pendent cord ornament r, and the 50 lower corner scroll-vine ornaments, s, all shaped and disposed substantially as represented in the aforesaid print.

The design for the skirting F consists of the flat arch t, having the series of circle ornaments u and the scroll-vine end ornaments, v, all shaped and arranged as shown in the accompanying engraving.

The design for the legs consists of the vine-like ornaments w on the inclined side wings, 70 w', central rectangular ornamented upper front part, x, ledge-molding x', central downwardly-tapering ornamented part, y, and the inclined ornamental side moldings, z, all shaped and combined as shown.

What we claim as our joint invention is—

1. The design for the hooded urn A, composed of the parts b e e' d d' d² d³, all shaped and arranged together as set forth.

2. The design for the end cap-plates, B, composed of the parts e f g h g' i, all shaped and arranged as set forth.

3. The design for the open-work balustrade C, consisting of the parts j k k l l', all shaped and combined as set forth.

4. The design for the side plate, D, composed of the compound ornaments m m and n n, severally shaped, composed, and arranged together as set forth.

5. The design for the end door, E, consisting 85 of the parts o, o', p, q, r, and s, all shaped and arranged as set forth.

6. The design for the skirting F, composed of the parts t, u, and v, all shaped and arranged as shown and described.

7. The design for the legs, consisting of the parts w w' x x' y z, all shaped and combined as set forth.

In testimony whereof we hereinunto set our hands, in the presence of two subscribing witnesses, this 15th day of November, 1881.

H. CLAY BASCOM,
CYRUS A. HODGES.

Witnesses:
